UNITED STATES PATENT OFFICE.

JOHN C. RAMSAY, OF BALTIMORE, MARYLAND.

GAS BURNER.

Application filed May 23, 1921. Serial No. 471,771.

To all whom it may concern:

Be it known that I, JOHN C. RAMSAY, a citizen of the United States, residing at Baltimore, in the county of Baltimore City and State of Maryland, have invented certain new and useful Improvements in Gas Burners; and I do declare the following to be a full, clear, and exact description of the invention, such as will enable others skilled in the art to which it appertains, to make and use the same.

This invention relates to improved gas burners such as are used in connection with stoves, ranges, coffee urns, and the like.

15 The principal object of the invention is to generally improve upon burners of this type by the provision of one of extreme simplicity and durability wherein the body is solely composed of a common inexpensive pipe-section which is in one instance, an elbow, and in another, a short threaded piece of pipe.

20 Another and very important object of the invention is to provide a burner having a body of the type above mentioned, together with an inverted conical flame spreader disposed over the upper open end of the body and detachably connected to the latter.

25 A further and very important object of the invention is to provide a burner where-in the arrangement and construction of parts is such that the entrance of dirt, drippings, and grease, to the piping is practically prevented. Thus, choking of the 30 pipes is overcome and frequent cleaning is unnecessary. This important feature should be carefully considered since it is not apparent in nor accomplished by the types of burners now patented and marketed.

35 Other objects and advantages of the improved burner will become apparent from the following description and the features and novelty will be pointed out in the appended claims.

40 In the accompanying drawings forming a part of this specification and in which like numerals are used to designate like parts throughout the same:

45 Figure 1 is an elevational view, with parts broken away and shown in section, of my improved burner, showing the same in use on a gas range.

50 Figure 2 is a central longitudinal sectional view of the rear or outer portion of the conduit.

Figure 3 is an elevational view, partly in section, of a slightly modified form of the invention.

55 Referring to the drawings by numerals, 1 designates the body of the burner which is 60 solely composed from a common elbow which is formed at the juncture of its horizontal and vertical portions with a screw-hole 1^a. A pin 2 screw-threaded at its opposite ends, has its lower end screwed into 65 this hole and its upper end extended above the corresponding end of the elbow as shown. It is onto this end that a solid conical casting 3, constituting a flame spreader, is screwed. This spreader is of 70 a diameter considerably greater than that of the elbow and it therefore provides a relatively large flame of even distribution and intense heat which will impinge the bottom of the cooking utensils and effect an extremely quick cooking of the contents 75 thereof.

80 Associated with the horizontal portion of the body 1 is a horizontal conduit 4, which is preferably made up of a long-screw 4^a formed in one side with an air inlet opening 5 and provided at its outer end with internal screw-threads into which a screw-nipple 6 is tapped. The construction of these parts may better be seen in 85 Fig. 2. Referring to this figure, it will be seen that the nipple 6 is formed at its outer end with a restricted smooth opening 7 which is designed to removably receive one end of the valved passage A 90 which connects with the main or supply pipe B of the range. Arranged on the screw-threads of the long-screw 4^a and longitudinally movable thereon, is a valve 8 which is adapted to cover and uncover the 95 air inlet opening 5 to admit more or less air as is desired or necessary to form the proper fuel mixture. In addition to the aforesaid parts, the conduit includes one or more lengths of pipe 9 connected to the 100 aforesaid part 4 by a reducer coupling 10. At this point, it may be stated that this conduit may be supported from the usual pan or other horizontal support on the range or stove by means of a suitable two-part bracket or clamp 11, which is preferably removable. This clamp may vary in 105 construction and its exact construction need not therefore be shown. However, it is to be understood that it is of such a construc-

110

tion as to prevent rotation or accidental displacement of the burner.

Reference being had to Fig. 3, it will be seen that I have disclosed a modified form 5 of burner which is especially, although not necessarily, designed for use with large coffee urns such as are seen in public eating houses. In this form of the invention 12 designates a vertical externally and internally threaded pipe having an air inlet 13 and a valve 14 for cooperation therewith. A nipple 15 for attachment to the usual valved supply pipe A' is threaded into the lower end of pipe 12, while a 15 cross-pin 16 is secured therein near the upper end thereof. This pin 16 is provided with a centrally disposed screw hole, and the lower end of the vertical rod 17 is threaded into it, the spreader 3, which has 20 been removed from the aforesaid rod 2, being screwed onto the upper end thereof.

In use, gas is fed through the pipes A and B and is permitted to enter the long-screw 4^a, which constitutes a mixing chamber since it is equipped with air supply means as described. The quantity of air passing into this chamber may be restricted by properly manipulating the valve 8, which, in actual use, is equipped on its outer 25 face with finger-gripping lugs as shown to facilitate in rotating it. The combined mixture of air and gas passes on through the remainder of this conduit and issues from the upper open end of the elbow where it is 30 ignited to form the flame. As can be seen, the flame plays upon the under face of the spreader plate and is diffused over the entire surface thereof and passes up and around the peripheral edge 17 and up 35 against the bottom of the utensil on the supporting grid above this plate. Thus, a free flow of gas is permitted and a hot uniform flame insured at all times.

From the foregoing description, it is obvious 45 that I have devised an extremely advantageous and desirable burner which is, in the main, made up of a few simple and inexpensive couplings and pipe-fittings, all of which are so connected that they can be 50 easily and readily separated for making repairs or for cleaning. This is an important feature and should be carefully considered, especially in view of the fact that the burner when so constructed, can be manufactured at an extremely low cost and can be retailed at a correspondingly low cost 55 to the purchaser. Then again, my flame spreader is such that it cannot be easily displaced and since it is made in the form of 60 a heavy casting, it is not very liable to be short-lived. Attention may also be directed to the fact that the spreader plate can be easily disconnected from the vertical supporting pin on the form of the invention 65 shown in Figs 1 and 2, and can be used on

the remaining form of the invention shown in Fig. 3. Moreover, the burner is such that grease and dripping fluids cannot enter the piping to choke the latter. Hence, frequent cleaning, as is necessary with the 70 common burner heads used, is entirely overcome. It may be added that although the burner is extremely simple in construction and likewise inexpensive for both the manufacturer and user, it is quite as advantageous and effective in operation as the more 75 expensive burners now used.

These and other advantages and features of the invention have, no doubt, become apparent from the foregoing description and 80 drawings. Therefore, a more lengthy and detailed description of the invention is deemed unnecessary.

I claim:

1. A gas burner comprising a body 85 formed from a common elbow having a screw-threaded hole formed therein at the juncture of its horizontal and vertical portions; a relatively small vertically disposed pin arranged in the vertical portion of said 90 elbow, being threaded at its lower end into said hole, and having its upper end screw-threaded and extending above the upper edge of the elbow; and a comparatively large solid inverted conical flame spreader 95 threaded onto the upper end of said pin, said spreader being considerably larger in diameter than the elbow and being spaced above the upper edge of the latter.

2. A burner for gas ranges comprising a 100 horizontal conduit including a long-screw having an air opening formed in one side and provided at its outer end with internal screw-threads, a ring-nut on said long-screw serving to cover and uncover said air inlet 105 opening, a screw-nipple tapped into said long-screw, having a smooth restricted intake opening for removably receiving the usual valved pipe leading from the main fuel supply pipe on the range, an elbow connected to the inner end of said conduit, and a stationary flame spreader arranged over the upper open end of said elbow, being 110 solely supported from the latter.

3. A gas burner comprising a horizontal 115 conduit including a long-screw having an air opening formed in one side and provided at its outer end with internal screw-threads, a ring-nut on said long-screw serving to cover and uncover said air inlet opening, a screw-nipple tapped into said long-screw, said nipple having a smooth restricted intake opening for removably receiving the usual valved pipe leading from the main fuel supply pipe of the stove, a 120 common elbow connected to the inner end of said conduit, said elbow having a screw threaded hole formed therein at the juncture of its horizontal and vertical portions, a relatively small vertically disposed pin 125

arranged in the vertical portion of said elbow and having its lower end threaded into said hole, the upper end of said pin extending above the upper edge of the elbow, and 5 a comparatively large inverted conical flame spreader threaded on to the upper end of said pin, said spreader being considerably

larger in diameter than the elbow and being spaced above the upper edge of the latter. 10

In testimony whereof I have hereunto set my hand.

JOHN C. RAMSAY.
